UNITED STATES PATENT OFFICE.

EDWARD BLOUNT, OF MORVEN, GEORGIA, ASSIGNOR TO DUNCAN J. MCEACHERN, OF SAME PLACE.

DESIGN FOR A BARREL-CLOSURE RING.

SPECIFICATION forming part of Design No. 28,746, dated May 31, 1898.

Application filed April 18, 1898. Serial No. 678,082. Term of patent 14 years.

To all whom it may concern:

Be it known that I, EDWARD BLOUNT, a citizen of the United States, and a resident of Morven, in the county of Brooks and State of Georgia, have invented and produced a new and original Design for Barrel-Closure Rings, of which the following is a specification, reference being had to the accompanying drawings, forming a part thereof.

Figure 1 is an upper perspective view of a barrel-closing ring showing my design. Fig. 2 is an under perspective view of the same.

My new design is shown in the accompanying drawings, and comprises a flat ring having a horizontally-presented outer periphery, a horizontally-presented inner periphery provided with diametric notches, a vertically-

presented annular flange between the inner and outer periphery, and two symmetrical inclined and segmental ridges presented vertically from the under side of the ring, near the inner periphery, and commencing with their lowest sides at the respective recesses in the inner periphery. 20

The leading features of my design are as 25 above enumerated.

I claim—

The design for a barrel-closure ring substantially as herein shown and described.

EDWARD BLOUNT.
